CLAIM

U.S. PATENT DOCUMENTS

The ornamental design for a combined basket and removable liner, as shown and described.

DESCRIPTION

D. 20,641 3/1891 Doty D34/44
D. 57,395 3/1921 Szonderowski D34/41
D. 57,535 4/1921 Loewenberg D34/42
D. 193,314 7/1962 Mangold D34/44
D. 268,217 3/1983 Stevens D34/42
D. 300,078 2/1989 McDuffie D34/43
2,425,564 8/1947 Ring 206/427
3,302,679 2/1967 Padovani 220/72

FIG. 1 is a perspective view of a combined basket and removable liner showing my new design;

FIG. 2 is a front elevation thereof;

FIG. 3 is a rear side elevation thereof;

FIG. 4 is a left side elevation thereof;

FIG. 5 is a right side elevation thereof;

FIG. 6 is a top plan view thereof; and

FIG. 7 is a bottom plan view thereof.

The broken lines shown in FIGS. 1 through 5 represent stitch lines.
